SENSITOMETRY

Stanley S. A. Watkins, London, England, assignor
to Electrical Research Products, Inc., New
York, N. Y., a corporation of Delaware

Application August 20, 1931, Serial No. 558,211,
and in Great Britain March 9, 1931

3 Claims. (Cl. 179—100.3)

This invention relates to the recording of modulated waves on a photographic film and particularly to the recording of sound on a photographic film by the variable area method.

5 The object of the invention is a means for readily obtaining a sensitometer record in the width of the film allotted to the sound track.

A feature of the invention is the provision of 10 switching means whereby predetermined values of current may be applied to the recording device.

In the variable area method of recording modulated waves, a small beam of radiant energy of constant intensity is directed on a sensitive 15 film and affects a portion of the width of the record track. A recording device actuated by modulated waves causes the beam to affect an area covering more or less of the width of the track. The control of the beam of radiant energy may be affected by reflecting the beam from 20 a mirror associated with the recording device to the film. The mirror is vibrated by the modulated waves and causes the area illuminated by the beam to be displaced laterally of the film. Or, the width of the beam may be defined by physical means, such as a shutter in 25 the recording device, and the movement of this shutter under the control of the modulated waves will cause a variation in the width of the beam laterally of the film.

In order to secure data for the proper control of the photographic processes, the density of the exposed and unexposed portions of the sound track must be measured. The density of the 30 sound track may conveniently be measured by known types of densitometers, such as a polarization photometer. The field of a densitometer of this type is usually approximately circular and cannot conveniently be reduced to a very 35 small area. In the known systems of recording in common use, the sound track is about $\frac{1}{4}$ inch wide, and when the beam is located in the center of the track, a strip of film $\frac{1}{16}$ inch wide is exposed and a similar strip is unexposed. 40 Owing to the small width of the strip, and the large field of the densitometer, the density cannot conveniently be measured.

In accordance with the present invention, 45 switching means are provided to control a biasing current which is applied to the recording device. In the normal position of the switching means, a normal bias is applied to the recording device and the recording beam causes an exposure of one-half of the width of the record track. In a second position of the switching

means the bias is changed so that the beam is completely removed from the record track and the full width of the track is unexposed. In a third position of the switching means, the bias is changed so that the beam covers the record 60 track and the full width of the track is exposed. Densitometer readings may then conveniently be made on the sections of the record track in which the full width is respectively 65 fully exposed or unexposed.

Fig. 1 discloses in schematic form a recording system embodying a preferred form of the invention.

Fig. 2 discloses a section of film produced by the invention.

In Fig. 1 sound waves may be detected by the microphone 1 and are amplified in the known manner in an amplifier or amplifiers. The output of the amplifier is applied to the primary winding of a suitable transformer 2. The output of transformer 2 is supplied through a large capacitor 3 to the movable strings 4, 5 of an oscillograph or galvanometer. The strings 4, 5 are partially immersed in the steady magnetic field of the magnet 6. A small mirror 7 is 80 affixed to the strings 4, 5. The reaction of the magnetic field due to an electric current flowing in the strings 4 and 5 with the magnetic field due to the magnet 6 will cause the mirror 7 to be vibrated.

Light from a suitable source 8 illuminates a small aperture in an opaque plate 9. This aperture preferably has the shape of a small, long rectangle. An image of the aperture is formed by the lens 10 on the mirror 7. The 90 light falling on the mirror 7 is reflected as a small rectangular beam which partially illuminates a small aperture in the plate 11. The light passing through the aperture in the plate 11 falls on a photographic film 12 which is moved 95 past the aperture by the sprockets 13, 14 which are rotated at constant speed in a known manner from a source of power, not shown. While, for convenience, a mirror galvanometer has been disclosed and described, it will be apparent to 100 those skilled in the art that many other types of light valves may be used and that the invention is not in any way limited by the galvanometer shown.

Current from a battery 15 flows through the 105 springs 16, 17, 18 and 19 of the key 28 and variable resistor 21 to the strings 4 and 5 of the galvanometer, thence through inductor 22 to battery 15. The capacitor 3 prevents this current from flowing in the secondary winding of 110

the transformer 2. This constant current flowing through the strings of the galvanometer causes the mirror 7 to be deflected. The result of biasing the mirror 7 as above described is illustrated in Fig. 2 at the points 23, 24 and 25 in the sound track on the film 26. When modulated currents are superimposed on this normal value of the biasing current, a conventional sound record is produced, as illustrated at 27 in Fig. 2. The reactor 22 prevents the modulated currents from being diverted through the biasing circuit.

To obtain a sensitometer record, before modulated currents are applied to the strings, the key 28 is operated to the right, opening the connection between the springs 16 and 17 and removing the biasing current from the strings 4 and 5 of the galvanometer. The galvanometer is mechanically adjusted so that when no current flows in the strings 4 and 5, the mirror 7 is deflected and the full width of the record track is unexposed, as illustrated at 29 in Fig. 2.

After a record of convenient length of the unexposed track has been made, the key 28 is restored to normal, closing the connection between springs 16 and 17 and causing the recording device to deflect the beam of light exposing one-half of the record track as illustrated at 30 in Fig. 2. The key 28 is then moved to the left opening the connection between springs 18 and 19 and closing a connection between springs 19 and 20. Current flows from battery 15, through springs 16 and 17, battery 30, springs 20 and 19, adjustable resistor 21, strings 4 and 5, through reactor 22 to battery 15. If the batteries 15 and 31 are of equal voltage, the mirror 7 will be deflected so that the full width of the record track is exposed as illustrated at 31 in Fig. 2. A record of the fully exposed track of convenient length is made and the key 28

may then be restored to normal. The circuit is then in condition to record modulated currents. What is claimed is:

1. In a film sound recording system of the variable area type, the method of making a sensitometer record which comprises mechanically adjusting the recording device so that a portion of the record track is substantially unexposed, applying a constant electric current to the recording device, manually adjusting said current so that another portion of the record track is exposed for substantially one-half of its width, and manually applying a further voltage such that said current is substantially doubled so that a further portion of said record track is exposed for substantially its full width. 80

2. In an apparatus for producing a sensitometer record in combination, means for producing a small beam of light, means for moving a sensitive film at constant speed past a small aperture, means for deflecting said beam to just fail to illuminate said aperture, means for manually applying an electric current to said deflecting means to cause said beam to illuminate substantially one-half of said aperture, and switching means for manually applying a further electric current to said deflecting means to cause said beam to illuminate substantially the whole of said aperture. 95

3. In an apparatus for producing a sensitometer record, in combination, means for producing a small beam of light, means for moving a sensitive film at constant speed past a small aperture, a recording device adjusted to deflect said beam to just fail to illuminate said aperture, and switching means for impressing at will two predetermined values of electric current on said recording device to cause said device to deflect said beam and illuminate said aperture to two predetermined degrees. 100
